COMBINED CONTAINER OPENER AND POURING SPOUT

Charles William Schild, Cary, Ill., assignor to American
Can Company, New York, N.Y., a corporation of New Jersey

Filed Sept. 8, 1964, Ser. No. 81,646

Term of patent 14 years

(Cl. D44—29)

Fig. 1.

Fig. 2.

Fig. 3.

FIG. 1 is a top perspective view of a combined container opener and pouring spout showing my new design;

FIG. 2 is an end elevational view taken from the left of FIG. 1; and

FIG. 3 is a perspective view thereof from the opposite angle and with the opener in inverted position.

I claim:

The ornamental design for a combined container opener and pouring spout, substantially as shown.
